COMBINATION TOOL

Joseph N. Amigone, Buffalo, N. Y.

Application October 23, 1948, Serial No. 149,261

Term of patent 14 years

(Cl. D44—29)

To all whom it may concern:

Be it known that I, Joseph N. Amigone, a citizen of the United States, residing at Buffalo, in the county of Erie and State of New York, have invented a new, original, and ornamental Design for a Combination Tool, of which the following is a specification, reference being had to the accompanying drawing, forming part thereof.

Figure 1 is a plan view of a combination tool, showing my new design; and

Figure 2 is an edge view thereof.

The essential features of the design reside in those portions shown in full lines on the drawing.

I claim:

The ornamental design for a combination tool, as shown and described.

JOSEPH N. AMIGONE.
